UNITED STATES PATENT OFFICE.

CHARLES DECRETTE, OF NEW YORK, N. Y.

METAL-BENDING MACHINE.

SPECIFICATION forming part of Letters Patent No. 674,574, dated May 21, 1901.

Application filed August 1, 1900. Serial No. 25,524. (No model.)

To all whom it may concern:

Be it known that I, CHARLES DECRETTE, a citizen of the United States, and a resident of the city of New York, borough of Manhattan, in the county and State of New York, have invented a new and Improved Metal-Bending Machine, of which the following is a full, clear, and exact description.

This invention relates to improvements in machines for bending metal bars; and the object is to provide a simple machine of this character by means of which the metal may be turned at a sharp angle at one operation and requiring but one heating of the metal, thus materially saving in time and consequent expense as compared with the bending-machines in which several heatings of the metal are required.

I will describe a metal-bending machine embodying my invention and then point out the novel features in the appended claims.

Reference is to be had to the accompanying drawings, forming a part of this specification, in which similar characters of reference indicate corresponding parts in all the figures.

Figure 1 is a plan view of a bending-machine embodying my invention. Fig. 2 is a front elevation. Fig. 3 is a section on the line $x-x$ of Fig. 2, showing the position of parts after bending a strip of metal. Fig. 4 is a section on the line $y-y$ of Fig. 2, and Fig. 5 is a section on the line $z-z$ of Fig. 2.

The machine comprises a base 1, from the rear side of which a standard 2 extends upward and forward, and on the upper end of this standard is a fixed bending-head 3 and a swinging bending-head 4. The upper end of the swinging head 4 swings on a lug 5, attached to the head 3, and the lower portion of this swinging head 4 has a block 6, from which a pivot-rod 7 extends downward through a bearing 8 and also through a bearing 9 at the lower end of the upright 2. Extended outward from the fixed head 3 is a table consisting of side bars 10 and 11, connected at the outer end to a block 12, from which a brace 13 extends downward to a connection with the base 1. Adjustable along this table, consisting of the bars 10 and 11, is an abutment-block 14, the body portion of which is provided at the front or inner side with a slot 15 in which the web of a wedge-

shaped adjusting-block 16 may slide, and this adjusting-block is held as adjusted by means, as here shown, of a pin 17, passing through openings in the block 14 and through either one of a series of openings in the block 16. The lower portion of the block 14 passes between the side bars 10 and 11 and is provided with toothed plates 18, designed to engage with teeth formed on the under side of said bars 10 and 11, so as to securely hold the block as adjusted lengthwise of the table. When adjusted, the parts may be clamped together by means of a bolt 19. 65

Extended outward from the swinging head 4 is a table similar to the first-named table—that is, it consists of the side bars 10 and 11 and the adjusting device movable thereon similar to the first-named adjusting device, 70 the parts being indicated by the same numerals.

At the inner end of the fixed table a holding-block 20 is mounted to slide against a guide-block 21 and underneath a guide-plate 22, secured on the upper side thereof. From this guide-block 20 an arm 23 extends outward, and from the arm 23 an arm 24 extends to a fixed connection with a rod 25. The arm 24 has pivotal connection with the arm 23, as 80 plainly shown in the drawings, and the rod 25 has bearings 26 and 27 at the inner end of the fixed table. The upper end of this fixed rod 25 is provided with a handle 28. A similar sliding guide-block 29 is adapted to move 85 on the inner end of the swinging table and is guided by the block 30 and the top plate 31, and on this block 29 is an arm 32, pivotally connected to an arm 33, extended from a vertical rod 34, provided with a handle 35 on its 90 upper end and having bearings at its lower portion in projections 36 37.

The holding-blocks 21 and 29 are provided on their inner surfaces or on the sides adjacent to the bending-heads with longitudinal 95 channels to receive the metal strip to be bent, as plainly indicated in Fig. 4. From the outer end of the swinging table a brace-rod 38 extends down to a connection with a collar 39, attached to the lower end of the pivot bolt or rod 7.

In operation the metal bar after being heated sufficiently is placed in the machine, as indicated clearly in Fig. 2—that is, it is

placed with the part to be bent against the bending-heads 3 and 4 when said heads are in alinement. Then the adjusting devices on the tables are to be moved up against the 5 ends of the strip and firmly clamped. The close or fine adjustments against the ends of the strips may be made by moving the wedge-shaped blocks 16. After this the rods 25 and 34 are to be turned in a direction to move the 10 holding-blocks 21 and 29 into engagement with the strip, the inner or adjacent ends of said holding-blocks being near the point to be bent. Now the swinging table is to be swung forward sufficiently to bend the strip 15 to the required angle. After the bending of course the rods 25 and 34 are to be rotated to disengage the holding-blocks 21 and 29 from the strip, so that it may be readily removed.

20 Having thus described my invention, I claim as new and desire to secure by Letters Patent—

25 1. In a machine for bending metal, a fixed bending-head, a bending-head mounted to swing, supporting-tables extended outward from said heads, adjusting devices movable on said tables, channeled holding-blocks, and means for sliding said holding-blocks toward and from each other lengthwise of the tables, 30 substantially as specified.

35 2. A machine for bending metal, comprising a stationary bending-head, a swinging bending-head, tables extended outward from said bending-heads and each consisting of two side bars, adjusting-blocks movable between the side bars, means for clamping said blocks as adjusted on the tables, wedge-

shaped adjusting-blocks for engaging with the first-named adjusting-blocks, longitudinally-movable holding-blocks provided with 40 channels to receive the bar to be bent, and means for moving said holding-blocks, substantially as specified.

3. A machine for bending metal, comprising a standard, a fixed bending-head on said standard, a bending-head mounted to swing relatively to the standard, tables extended outward from said heads, adjustable clamping or adjusting blocks movable on said tables, holding-blocks movable toward and 45 from each other provided with channels to receive the bar to be bent, vertical rotary rods, arms extended from said rods and having pivotal connection with the holding-blocks, and guides for said blocks, substantially as specified.

4. A machine for bending metal, comprising a standard, a fixed bending-head on said standard, a bending-head mounted to swing on said standard, tables extended outward 60 from the heads, one being mounted to swing with the swinging head, clamping or adjusting devices having locking engagement with said tables, and devices for engaging a bar to be bent near its point of bending, the said devices being mounted to slide, substantially as specified.

In testimony whereof I have signed my name to this specification in the presence of two subscribing witnesses.
